SUCTION CLEANER

Eugene L. Snyder, Canton, Ohio, assignor to The Hoover Company, North Canton, Ohio, a corporation of Ohio

Application April 29, 1940, Serial No. 332,217

11 Claims.

(Cl. 15—16)

This invention relates to improvements in suction cleaners and more particularly to an improved and novel arrangement of the essential elements of a portable handle-maneuvered suction cleaner calculated to provide a more compact assembly and to impart a low streamlined appearance.

Therefore, one of the objects of the present cleaner design is to bring about the appearance of reduced height by recessing the top of the main casing and mounting the motor therein.

A further object of the invention is to provide a suitable ventilating system for a recessed motor mounting, a system characterized by air inlet ports formed in marginal wall segments of the removable motor hood covering those portions of the motor receiving recess not covered by the hood proper.

The features of the improved cleaner design hereinabove noted as well as others of lesser importance are disclosed in the accompanying drawings, in which:

Figure 1 is a view of the cleaner in side elevation with portions of the main casing and motor hood broken away to show the internal design;

Figure 2 is a perspective view of the cleaner completely assembled with the exception of the motor cover; and

Figure 3 is also a perspective view of the cleaner with the motor hood assembled and portions of the hood and main casing removed so as to show the internal structure generally and more particularly the inlet ports and passages for the motor ventilating air.

The body of the cleaner herein disclosed consists of a cast metal casing 1 mounted upon pairs of front and rear wheels 2, 2 and having at its forward end a nozzle portion 3 in the form of a chamber 3a extending the full width of the casing and opening downwardly to provide a suction mouth 3b.

The casing 1 is cast with a fairly deep recess 4 covering practically its entire top area with the exception of narrow marginal portions along the sides, rear and downwardly curved front face of the nozzle portion 3, as clearly shown in Figure 2.

Within this recess 4 is mounted the motor 5, and immediately behind the motor is a bracket 6 upon which is pivotally mounted the socketed fitting 7 supporting the cleaner-maneuvering handle.

Located centrally of the recessed top wall of the casing 1 is a second recess or cavity 8 of considerably less diameter but of approximately the same depth as the recess 4, this cavity forming 55

the side walls and bottom wall of a fan chamber for the suction-creating fan 9 mounted at the lower end of the armature shaft of the motor 5 and forming therewith a complete unit. The fan chamber communicates with an exhaust passage leading rearwardly and terminating in an outlet connection 10 to which is removably attached a dirt bag 11 supported from the handle at its outer end in the usual manner.

Referring now to the structural details of the motor 5 and its assembly on the main casing 1, the motor frame is preferably of a two-part construction of molded Bakelite or other suitable molded plastic substance, and consists of a cylindrical top section 5a and a somewhat rectangular base section 5b, with the parting line between the two parts just below the top wall of the latter. Within the motor frame is mounted a vertically arranged armature 12 and a field stack 13, the latter being of the uni-coil type, thus accounting for the forward protrusion of the base section of the motor frame and its somewhat unbalanced appearance. The sections of the motor frame are fastened together by the usual arrangement 20 of screws passing through and anchored in bosses 14, and the upper end of the frame is preferably surmounted by a removable cap 15 supporting the upper armature shaft end bearing.

The bottom wall 16 of the motor frame is of 30 substantial thickness and includes a structurally reinforced flange 16a extending entirely around the base of the motor and following the generally circular but somewhat irregular contour of the fan chamber. The under face of the bottom wall 35 16 of the motor casing or frame is preferably covered or lined with a thin metal sheet 17 which forms the top wall of the fan chamber and, with its margins offset slightly and overlapping the edges of the fan chamber cavity 8, is suitably anchored in place to complete the motor mounting.

With this arrangement, it will be seen that the 40 flanged bottom wall 16 of the motor frame with its metal liner 17 forming the top wall of the fan chamber eliminates the need for a separate fan chamber top wall and thus aids in reducing the height of the cleaner accordingly. However, to take advantage of this height reduction it is necessary that the flanged bottom wall of the motor frame shall be commensurate with the diameter of the fan chamber and this accounts for the large area covered by the recess 4, extending as it does practically the full width of the casing 1, as well as the major portion of its length. In short, the recess could be considerably less in both longitudinal and transverse di-

mensions if the accommodation of the motor were the only consideration.

This extended area of the recess 4 is also reflected in the design and construction of the cover or hood member 18 which normally extends over and conceals the motor, wiring, and the floor-illuminating lamp mounted forwardly of the motor and presently to be described. In its general appearance, the cover 18 resembles a box-like hood or dome, relatively shallow and sloping toward its rear end. The hood or dome portion 18a of the cover is dimensioned to enclose only that portion of the motor frame projecting above the main casing 1, although it does extend rearwardly to the back edge of the main casing on either side of the handle mounting. Otherwise, the dome portion 18a is considerably narrower than the width of the recess 4 and also terminates short of its front edge with the result that it is necessary to provide laterally extending flanges or wall segments 18b along the sides and across the front of the dome portion 18a to cover the remaining area of the recess 4. The wall segments 18b overlie and seat around the edges of the recess 4, with the forwardly extending segment flush with a raised panel 19 curving downwardly over the front face of the nozzle portion 3.

Referring now to the ventilating or cooling system with which the motor 5 is equipped, provision is made for admitting atmospheric air at the base of the motor frame through a port 20 at its front end and opening into the space immediately below the field stack 13 and just above its bottom plate 16. The air then passes upwardly and around the armature and field stack, as indicated by the arrows in Figure 1, the circulation being induced by an auxiliary fan 21 mounted on the armature shaft just above the commutator 22 and rotating within its own fan chamber formed in part by the cap member 15 and separated from the space within the motor frame just below. The ventilating fan chamber has an exhaust opening 23 facing forwardly and substantially in line with a transversely elongated opening or window 24 in the front vertical wall of the dome portion 18a of the motor hood 18.

As clearly shown in Figure 1, there is mounted between the exhaust outlet 23 from the ventilating fan chamber and the window 24, a lamp 25 together with a suitable lamp bracket 26 supported upon the motor frame. This lamp performs the usual function of illuminating the floor immediately in front of the cleaner, the light therefrom being directed through the window 24, which, being open, serves also as an outlet port for the ventilating air. It will be noted that the air passing over and around the lamp on its way from the upper end of the motor to the window 24 also serves to dissipate the heat emanating from the lamp while the cleaner is in operation.

Having identified the inlet port 20 at the base of the motor frame and through which the air is admitted for cooling and ventilating purposes, it now remains to identify the inlet openings and passage leading from the atmosphere to said inlet port 20.

Referring first to Figure 2, it will be noted that a narrow portion 27 of the recess 4 in top of the main casing extends transversely thereof just above the nozzle chamber and is divided off from the major portion beyond by a pair of upstanding web 28, 28 extending inwardly at right angles 70

from the opposite walls of the recess and terminating in rearwardly curved end portions 28a, 28a spaced apart the width of the inlet port 20 and framing the same between them. So also, 5 when the motor cover 18 is fitted in place, forwardly extending portion of its marginal wall segment 18b forms the top wall of this cavity 27 and, by virtue of a pair of depending webs 29, 29 on its undersurface complementing the upstanding webs 28, 28 on the main casing 1, these pairs of coating webs abut each other edgewise, thereby converting the cavity 27 into a transverse passage communicating with the inlet port 20 to the motor frame. And finally, inlet ports 10 18, 30, suitably arranged in the forwardly extending marginal wall portion 18b of the motor hood, admit air from the surrounding atmosphere into the passage 27. This provides a convenient arrangement for supplying air to the ventilating system and especially so since the exhaust outlet 23 at the upper end of the motor frame opens directly into the space enclosed by the dome portion of motor cover 18, and hence the inlet passage for the ventilating air must be closed off 15 from that space in order to maintain the circulation of air through the motor. Otherwise, there would be a short circuiting of the motor ventilating air from the exhaust at the top directly to the inlet port at the bottom of the motor casing.

Thus apart from the provision herein made for conducting the ventilating air to and from the motor, the merit of the present cleaner design resides in the lowering of the motor with respect to the body of the cleaner by recessing the top surface of the latter and utilizing the bottom plate of the motor assembly as the top wall of the fan chamber, thereby giving the cleaner the appearance of decreased height and more pleasing lines throughout. Also, the recessing of the cleaner body provides the necessary space for the air inlet passage to the motor.

Having set forth the novel features of the design embodying the invention, but without any desire or intention of being limited to the precise disclosure herein, I claim:

1. In a suction cleaner, the combination of a casing including a nozzle chamber and a fan chamber communicating with said nozzle chamber, said casing being relatively deeply recessed substantially throughout the top surface area thereof, a motor mounted within said recess with a cavity extending around the base thereof and having ports adjacent opposite ends thereof for the circulation of cooling air therethrough, and a cover member extending over the exposed portion of said motor and having laterally projecting marginal wall segments seating around the edges of said recess and closing off a portion of said cavity to form an air passage communicating with the ventilating port at the base of said motor frame, one of said marginal wall segments having an opening therein connecting said air passage with the atmosphere.

2. In a suction cleaner, the combination of a casing including a nozzle chamber and a fan chamber communicating with said nozzle chamber, said casing having a relatively deep recess extending substantially throughout the upper surface thereof, a motor mounted within said recess with its base portion spaced from the side walls of said recess, said motor having an enclosed frame provided with ports adjacent its base and upper end for the circulation of cooling air therethrough, and a cover member extending

over said motor and having an opening communicating with the port at the upper end of the motor frame and laterally projecting marginal wall segments supporting said cover member upon the edges of said recess and closing off a space adjacent the ventilating port in the base of said motor frame to form an air passageway, the marginal segment over said passageway having a port therein communicating with the atmosphere.

3. In a suction cleaner, the combination of a casing including a nozzle chamber, a fan chamber communicating with said nozzle chamber, said casing having a relatively deep recess extending substantially throughout the upper surface thereof, a motor mounted in said recess and comprising a frame provided with ports at its base and upper end for the circulation of cooling air therethrough, said motor being spaced from the front edge of said recess with an open cavity therebetween, a cover member comprising a dome-like portion fitting over the projecting portion of said motor and having an opening communicating with the ventilating port at the upper end of said motor frame and laterally projecting marginal wall segments adapted to seat around the edges of said recess, a portion of the cavity extending along one side of said motor being closed off by one of said marginal wall segments to form a passageway communicating with the ventilating port at the base of the motor frame and having an opening therethrough connecting said passageway with the atmosphere.

4. In a suction cleaner, the combination of a casing including a nozzle chamber, a fan chamber communicating with said nozzle chamber, said casing having a relatively deep recess extending substantially throughout the upper surface area thereof, a motor mounted in said recess and comprising a frame provided with ports at its base and upper end for the circulation of cooling air therethrough, said motor being spaced from the front edge of said recess with an open cavity therebetween, a cover member comprising a dome-like portion enclosing the projecting portion of said motor and having an opening communicating with the ventilating port at the upper end of said motor frame and laterally projecting marginal wall segments adapted to seat around the edges of said recess, and vertical wall segments closing off the portion of said cavity extending transversely in front of said motor to form a passageway communicating with the ventilating port at the base of said motor frame, the forwardly projecting marginal wall segment of said cover member closing the top of said passageway and having openings therein to the atmosphere.

5. In a suction cleaner, the combination of a wheeled casing including a nozzle chamber and a fan chamber communicating with said nozzle chamber, said casing having an upwardly opening recess in its top wall extending rearwardly from said nozzle chamber substantially throughout the area above said fan chamber, a motor mounted within said recess comprising a frame having ports at its lower and upper ends for the circulation of cooling air therethrough, the portion of said recess immediately forward of said motor being partitioned off from the remainder thereof to form an open cavity communicating with the port at the base of said motor frame, and a cover member including a dome portion extending over the motor and having an opening therein adjacent the ven-

tilating port in the upper end of said frame and a forwardly projecting marginal wall segment extending over said cavity to form an air passage and having ports therethrough to the atmosphere.

6. In a suction cleaner, the combination of a wheeled casing including a nozzle chamber and a fan chamber communicating with said nozzle chamber and having an upwardly opening recess 10 rearwardly of said nozzle chamber and above said fan chamber, a motor mounted on said casing with its base portion depressed in said recess and comprising a frame having ports at its lower and upper ends for the circulation of cooling air therethrough, the forward portion of said recess immediately above said nozzle chamber being partitioned off from the remainder of said recess by a pair of upstanding webs to form a cavity open to the port at the base of said motor frame, and a cover member including a dome portion extending over the motor and having an opening therein adjacent the port in the upper end of said motor frame and a well portion projecting forwardly from the base of said dome portion and over said cavity to form an air passage and having ports therethrough for connecting the same with the atmosphere.

7. In a suction cleaner, the combination of a casing including a nozzle chamber and a fan chamber communicating with said nozzle chamber and having an upwardly opening recess rearwardly of said nozzle chamber and above said fan chamber, a motor mounted in said recess and comprising a frame having ports at its lower and upper ends for the circulation of cooling air therethrough, the forward portion of said recess immediately above said nozzle chamber being partitioned off from the remainder of said recess by a pair of transverse webs to form a cavity open to the port at the base of said motor frame, a cover member including a dome portion extending over the motor and having a window opening in the front wall thereof open to the port of the upper end of said motor frame, and a lamp mounted under said dome portion adjacent said window opening, said cover member including a forwardly extending wall segment extending over said cavity to form an air passage with ports in the top wall thereof opening to the atmosphere.

8. A suction cleaner comprising a cleaner body having a nozzle at its forward end, a fan chamber spaced rearwardly of said nozzle, a suction passageway connecting said nozzle with said fan chamber, said body having in its top surface an upwardly opening recess extending rearwardly from said nozzle, a portion of the bottom wall of said recess forming the top wall of said suction passageway, a motor mounted in said recess and overlying said fan chamber, said motor being spaced from the side walls of said recess and projecting upwardly from said recess above the cleaner body, and a housing including a hood enclosing the projecting portion of said motor, a wall extending laterally outwardly from the bottom edge of said hood and supported on said body along the marginal edge of said recess, said wall spanning the space between said motor and the side walls of said recess.

9. A suction cleaner comprising a cleaner body having a nozzle at its forward end, a fan chamber spaced rearwardly of said nozzle, a suction passageway connecting said nozzle with said fan chamber, said body having in its top surface an upwardly opening recess extending rearwardly

from said nozzle, a motor mounted in said recess and projecting upwardly above the cleaner body, the side walls of said recess enclosing in spaced relation that portion of the motor in said recess, and a housing including a hood enclosing the projecting portion of said motor, a wall extending laterally outwardly from the bottom edge of said hood and supported on said body along the marginal edge of said recess, said wall spanning the space between said motor and the side walls of said recess.

10. A suction cleaner comprising a cleaner body having a nozzle at its forward end, said body having in its top surface an upwardly opening recess extending rearwardly from said nozzle, a motor mounted in said recess and spaced from the side walls of said recess and projecting upwardly from said recess above the cleaner body, and a housing including a hood enclosing the projecting portion of said motor, a wall extending laterally outwardly from the lower edge of said hood and supported on said body along the marginal edge of said recess, said wall spanning the space between said motor and the side walls of said recess, means on said laterally extending wall cooperating with means on said recess wall to define a motor ventilating air passageway communicating with said motor, and a ventilating port in said laterally extending bottom wall communicating

with said passageway and the atmosphere for cooling said motor.

11. A suction cleaner comprising a cleaner body having a nozzle at its forward end, a fan chamber spaced rearwardly of said nozzle, a suction passageway connecting said nozzle with said fan chamber, said body having in its top surface an upwardly opening recess extending rearwardly from said nozzle, a portion of the bottom wall of said recess forming the top wall of said suction passageway, a motor mounted in said recess and overlying said fan chamber, said motor being spaced from the side walls of said recess and projecting upwardly from said recess above the cleaner body, a housing including a hood enclosing the projecting portion of said motor, a wall extending laterally outwardly from the bottom edge of said hood and supported on said body along the marginal edge of said recess, said wall spanning the space between said motor and the side walls of said recess, said laterally extending wall cooperating with a top wall of said suction passageway to define a motor ventilating air passageway communicating with said motor, and a ventilating port in said laterally extending bottom wall communicating with said passageway and the atmosphere for cooling said motor.

EUGENE L. SNYDER.
